FINGER RING

George A. Armstrong, Cranston, R. I., assignor
to William C. Greene Company, a corporation
of Rhode Island

Application April 23, 1936, Serial No. 75,964

5 Claims. (Cl. 63—15)

5 My invention relates to finger rings particularly adapted to afford settings for jewels, gems, stones, ornaments, and the like, and is of the sheet metal type in distinction from cast type of ring.

An object of my invention is to afford a ring structure and method of construction adapted to accommodate ornaments of any usual or preferred contour, such, for instance, as square, 10 oval, octagon or polygonal, without any substantial change in the ring structure.

Further objects are to effect the above ends with a minimum of parts, adapted for facile and speedy assemblage, and at a small expense in 15 either tools or structural labor.

With the above and other objects in view, all of which will fully appear in the course of the following description, my invention consists in such parts and in such combinations of parts, 20 and in such steps and such succession of steps, as fall within the scope of the appended claims.

In the accompanying drawings are illustrated certain preferred forms of my invention, wherein

Figures 1 and 2 are a plan view and edge elevation respectively of the original blank from which the shank member of my finger ring is made,

Figures 3, 4, and 5, a side elevation, front elevation, and plan view respectively of a finger ring of the prong type formed from the above mentioned blank carrying a rectangular or cushion shaped ornament,

Figures 6 and 7, sections of the same taken on lines 6—6 and 7—7 of Figures 5 and 3 respectively,

Figures 8, 9, and 10, a front elevation, central transverse section, and top plan view respectively of one of the lateral bars of the finger ring,

Figure 11, a fragmentary section taken on line 11—11 of Figure 5,

Figures 12 and 13, a plan view of the shank blank and a front elevation of one of the bars respectively from which are formed a modification of the prong type of my invention,

Figure 14, a fragmentary side elevation of the ring formed from the last mentioned elements,

Figure 15, a section of the same taken on line 15—15 of Figure 14,

Figures 16 and 17, a plan view of the shank blank and a front elevation of one of the bars respectively from which is formed a finger ring of the box type embodying my invention,

Figure 18, a fragmentary perspective view of 55 a complete ring of the box type,

Figure 19, a top plan view of a finger ring of my invention carrying an oval shaped stone,

Figure 20, an edge elevation of the shank blank employed in the same,

Figure 21, a section taken on line 21—21 of 5 Figure 20, and

Figures 22 and 23, a front elevation and central transverse section respectively of one of the lateral bars of the structure of Figure 19.

Similar characters of reference indicate similar parts throughout the views.

The following is a description of my invention in conjunction with the above drawings.

By suitable tools a blank 25, shown in Figures 1 and 2, is cut from thin sheet metal consisting of 15 shank 26 and terminal bearing portions 27, each comprising a head 28, a bearing flange 29 projecting from the end of the head, and lateral ears 30 provided with perforations 31. The flanges 29, in this instance, are located midway of 20 the end of the heads leaving spaces 32 at both sides of the flanges, thus forming bearing flanges of the prong type.

By a forming tool the blank is centrally circularly bent to shape the shank 26 into semi- 25 annular form with the terminal bearing portions 27 spaced from each other. The latter are connected by independent lateral bearing portions or bars 34 cut and bent by suitable tools from a flat metal blank. Each bar comprises a 30 straight elongated body 35 provided with a concave lower edge, as at 36, an inwardly directed longitudinally disposed retaining flange 37 upon its upper portion above an internal shoulder 38 at the base of the flange, and lugs 41 upon the end 35 of the body. The flanges 37 being less in width than the body cause end spaces 40. The lugs are engaged with the ears 30 in the perforations 31 by friction, or solder. A stone, gem, or other ornament 43 in this instance is of rectangular 40 or cushion shape, and is seated at two of its ends upon the shoulders 38 of the bars 34 whose prong flanges 37 overlap and retain said ends. The other two edges of the member 43 are engaged by the bearing flanges 29. The above construction is shown in Figures 1 to 11 inclusive.

Another form of the prong type of my invention, shown in Figures 12 to 15 inclusive, consists mainly in changing the perforations in the heads 28 to the lateral bars, and in omitting the lugs upon 50 the lateral bars and utilizing lateral ears or lugs upon the heads in place thereof. This construction in more detail is as follows.

The blank 45 of Figure 12 differs from the blank 25 of Figure 1 merely in substituting for the ears 55

or lugs 30 with perforations 31, imperforate ears or lugs 46 of slightly less dimensions. The bar 48 of Figure 13 is similar in construction to that of the lateral bearing portion or bar 34 of Figures 9 and 10, except that the end lugs of the latter are omitted, and perforations 49 are provided in the end margins of the bar adapted to receive the ears or lugs 46.

My invention is capable of embodiment also in a ring structure of the box type and is herein so illustrated in Figures 16 to 18 inclusive. The blank 51 shown in Figure 16 resembles the blank 25 in Figure 1 except the bearing flanges 53 of the former extend throughout the entire length of the forward edge of the heads 28 thus obviating the end spaces 32 of the blank 25. The bars 55, one of which is shown in Figure 17 resembles in detail the bar 34 of Figures 8, 9, and 10 except that the end recesses 40 of the latter figure are omitted and the bearing edge 56 extends the length of the bars 55. It is obvious by reference to the showing and description of the alternative form of construction of the prong type disclosed in Figures 12 to 15 inclusive that it is equally applicable to the box type.

The principle of my invention lends itself to embodiment with stones of various peripheral contours or shapes, as for instance as oval, octagon and the like. This is rendered possible by reason of the fact that no radical change is required in the constituent blanks over those already described.

For example a finger ring 59, shown in Figure 19, accommodating an ornament 60 of oval shape is composed of a blank 62 similar to that shown in Figure 1 except that the terminal bearing portions 63 are transversely curved rather than transversely straight, which curvature is easily effected by a finishing tool. The lateral bearing members 66 are identical with the bearing members 34 of Figure 10 except that they are longitudinally curved rather than straight, a change imparted by a finishing tool.

I claim:—

1. In a finger ring, a shank, terminal bearing members including heads upon the shank, bearing flanges upon the ends of the heads, and laterally extending portions upon the heads provided with perforations, lateral bearing members comprising

elongated bodies, bearing flanges upon the tops of the bodies, internal longitudinal shoulders upon the bodies below the last mentioned flanges and terminal lugs upon the bodies registering in the perforations, and an ornament resting upon the shoulders and engaged by the flanges upon the heads and by the flanges upon the bodies.

2. In a finger ring, a shank, a pair of terminal bearing members upon the shank, and a pair of lateral bearing members comprising elongated bodies, internal longitudinal shoulders upon the bodies adapted to support an ornament, bearing flanges upon the bodies above the shoulders adapted to engage an ornament, one pair of bearing members being provided with perforations, and the other pair of bearing members being adapted to register in the perforations.

3. In a finger ring, a shank, a pair of terminal bearing members upon the shank, a pair of lateral bearing members comprising elongated bodies, bearing flanges upon the tops of the bodies, and internal shoulders upon the bodies below the flanges, one pair of bearing members being provided with perforations, and the other pair of members being registerable in the perforations, and an ornament resting upon the shoulders and engaged by the flanges and by the terminal bearing members.

4. In a finger ring, a shank, a pair of terminal bearing members including heads upon the shank, and bearing flanges upon the ends of the heads, a pair of lateral bearing members comprising elongated bodies, bearing flanges upon the tops of the bodies, and internal longitudinal shoulders upon the bodies below the flanges, said heads having parts for interengagement with the lateral bearing members, and an ornament resting upon the shoulders and engaged by the flanges upon the heads and by the flanges upon the bodies.

5. In a finger ring, a shank, a pair of terminal bearing members upon the shank, an ornament, a pair of lateral bearing members comprising elongated bodies, supporting elements upon the bodies, and retaining elements upon the bodies cooperating with the supporting elements for engaging the ornament, said terminal bearing members having parts for interengagement with the bodies of the lateral bearing members.

GEORGE A. ARMSTRONG.
